UNITED STATES PATENT OFFICE

JOSEPH R. MORTON, OF STEUBENVILLE, OHIO

TOOL

Application filed May 2, 1932. Serial No. 608,796.

This invention relates broadly to tools and has more particular reference to a tool especially designed for removing the broken axle shaft of well known make of automobiles, it being of course understood that the tool is not limited to the use just mentioned but will be also found useful for other work as will be appreciated by those skilled in the art.

The invention together with its objects and advantages will be best understood from a study of the following description, taken in connection with the accompanying drawings wherein:

Figure 1 is a sectional elevational view through the rear end of a well known type of vehicle showing the application of the invention for removing a broken axle.

Figure 2 is a view taken at substantially right angles to Figure 1.

Figure 3 is a side elevational view of the tool.

Figure 4 is a top plan view thereof.

Figure 5 is a longitudinal sectional view taken substantially on the line 5—5 of Figure 3.

Figure 6 is a transverse sectional view taken substantially on the line 6—6 of Figure 5, and

Figure 7 is a plan view of an end portion of a rod forming part of the invention.

With reference more in detail to the drawings it will be seen that the improved tool comprises a relatively elongated barrel 10 open at one end and provided at said end with relatively spaced parallel coextensive work straddling extensions or arms 11. Slidably arranged within the barrel 10 and normally projected outwardly through the open end thereof is a hollow cylindrical plunger 12 that serves to reinforce the arms 11 and to prevent buckling thereof. A rod 13 has one end slidably engaged with the plunger 12, and as shown, said rod 13 at said one end is provided with a disk like head 14 that is arranged within the plunger 12 after which the wall of the plunger at the open end thereof is bent inwardly in a well known manner to restrict the opening at said end of the plunger and to provide a flange with which the head 14 is engageable to prevent with-

drawal of said end of the rod from the plunger. At its free end the rod 13 is slidable through an opening 15 provided in the substantially closed end of barrel 10 and said free end of rod 13 is provided with a threaded pin 13a adapted to be screwed into a threaded socket provided on one end of an elongated cylindrical handle member 16 provided for said rod 13.

At said socketed end the handle member 16 provides a shoulder 17 arranged to engage the adjacent end of the barrel 10 for limiting inward movement of the rod 13, rod 13 being normally urged inwardly of the barrel, and plunger 12 being normally urged outwardly of the barrel by the spring 18 disposed about the rod 13, said spring 18 having one end bearing against the end wall of the barrel 10 and the other end thereof bearing against the inner end of the plunger 12 as shown in Figure 5.

In Figures 1 and 2 is shown the manner of use of the tool for removing a broken axle, and in these figures 19 designates the transmission housing, 20 the axle housing, and 21 the broken axle. To remove the broken axle the unbroken axle shaft is removed and the tool is inserted in the end portion of the axle housing 20 from which the unbroken axle shaft has been removed, the finger equipped end of the barrel 10 passing through one of the transmission gears 22 into engagement with the inner end of the broken axle shaft 21, the extensions 11 straddling the pinion gear shaft 23 of the differential. It is apparent and as shown in Figure 2, that as the barrel 10 is moved inwardly to engage the end of the extension 11 with the broken axle shaft 21, that the outer end of the plunger 12 being engaged with the differential shaft 23 will be forced inwardly of the barrel against the action of the spring 18 and relative to the rod 13. In forcing the ends of the extension 11 into engagement with the end of the broken axle shaft 21 shoulder 17 will engage the proximate end of the barrel 10 and with a suitable tool such as a hammer or the like the outer free end of the handle 16 is struck with sufficient force for continuing the movement of the tool toward the left in Figures 1 and 100.

2 and thereby force the broken axle shaft 21 in a corresponding direction and through the axle housing 20.

It is apparent that from the foregoing an 5 ejection of the broken axle 21 may be readily accomplished with a tool of this character without requiring the mechanic to assume a position beneath the automobile and that also the handle 16 may be of any suitable length 10 to facilitate the operation.

Even though I have herein shown and described the preferred embodiment of the invention, it is to be understood that the same 15 is susceptible of further changes, modifications and improvements coming within the scope of the appended claims.

Having thus described my invention, what I claim as new is:

1. A tool of the class described comprising 20 a barrel open at one end and being provided at said one end with a pair of spaced parallel arms adapted to straddle the gear shaft of the differential gearing of a rear axle assembly and to engage the inner end of the inner 25 portion of a broken axle of said assembly, a plunger for reinforcing said arms arranged to reciprocate in said barrel and movable inwardly and outwardly thereof between said arms, and spring means arranged in said barrel and engaging said plunger to normally urge the latter outwardly of said barrel.

2. A tool for removing broken vehicle axles comprising a barrel provided at one end with 30 a pair of coextensive arms adapted to be passed into the differential housing of the vehicle to engage an end of the broken axle, a plunger normally projected outwardly of the barrel between said arms for reinforcing said arms, said plunger having its outer end adapted 35 to engage the gear shaft within the differential housing and to move inwardly of said barrel as the latter is moved in a direction for displacing the broken axle, a rod having an end slidably engaged with said plunger, and 40 a second end extending through the end of said barrel remote from said arms, a handle for said rod, means for connecting one end of said handle with the last named end of said rod for limiting inward movement of said rod, and a spring arranged in said barrel and 45 bearing against one end of said plunger for normally urging the same outwardly of said barrel.

In testimony whereof I affix my signature.

JOSEPH R. MORTON.
